UNITED STATES PATENT OFFICE.

ROBBIE L. ADKINS, OF OMAHA, NEBRASKA, ASSIGNOR OF ONE-HALF TO JAMES W. HOPKINS, OF OMAHA, NEBRASKA.

DESIGN FOR A FLOWERPOT STAND.

Application filed March 24, 1922. Serial No. 1,377. Term of patent 7 years.

To all whom it may concern:

Be it known that I, ROBBIE L. ADKINS, a citizen of the United States, residing at Omaha, in the county of Douglas and State of Nebraska, have invented a new, original, and ornamental Design for a Flowerpot Stand, of which the following is a specification, reference being had to the accompanying drawing, forming part thereof.

I claim:

The ornamental design for a flower pot stand, as shown.

ROBBIE L. ADKINS.
